CLAIM

The ornamental design for a sports training device as shown and described.

DESCRIPTION

FIG. 1 is a left side perspective view of the sports training device of the present disclosure;

FIG. 2 is a right side perspective view thereof;

FIG. 3 is a right side view thereof;

FIG. 4 is a left side view thereof;

FIG. 5 is a top view thereof;

FIG. 6 is a bottom view thereof;

FIG. 7 is a right end view thereof; and,

FIG. 8 is a left end view thereof.

The evenly dashed broken lines indicate unclaimed portions of the sports training device that form no part of the claimed design.
